UNITED STATES PATENT OFFICE.

JOSEPH WARNER, OF HARTFORD, CONNECTICUT, ASSIGNOR OF ONE-HALF
TO ADALBERT J. WARNER, OF CHICAGO, ILLINOIS.

KEY-HOLE GUARD.

SPECIFICATION forming part of Letters Patent No. 275,553, dated April 10, 1883.

Application filed August 6, 1881. (Model.)

To all whom it may concern:

Be it known that I, JOSEPH WARNER, of Hartford, in the county of Hartford and State of Connecticut, have invented a certain new and useful Improvement in Door-Locks, of which the following is a description, reference being had to the accompanying drawings, where—

Figure 1 is a view of the front side of a mortise-lock bearing my improvement, meaning by "front side" that side which faces the outside of the room when the lock is set into a room-door. Fig. 2 is a view of the same lock from the same side with the front plate removed. Fig. 3 is an edge view of said front plate. Fig. 4 is a rear view of said front plate. Fig. 5 is a view of the key.

The lock is one which bears on the front a guard-plate capable of reciprocating motion, which is not operated when the lock is operated by inserting the key from the front, but which is moved over the key-hole when the bolt is thrown into "locked" position with the key inserted from the rear, and vice versa, so that a person entering his room and locking his door by the same act moves a guard-plate over the key-hole on the outside.

The letter *a* denotes the lock-case; *b*, the removable front plate thereof; *c*, the bolt, appurtenant to which there may be the usual appliances of tumblers, springs, &c. On the outside of the front plate, *b*, there is a reciprocating guard-plate *d*, which covers or uncovers the key-hole *e*, according as it is at one end or the other of its play. It may be kept to its seat by the headed rivet *f*, moving in the mortise *g*. A pin, *h*, practically integral with the guard-plate, plays in this same mortise and

engages with the pivoted lever *i*. On the side of the bolt there is pivoted the pawl *j*, pressed downward by the spring *k* against the stop *l*, and provided with the two slots *m* and *n* in its lower edge. When the lock is operated by the key inserted from the rear the upper end of the lever *i* constantly engages with the slot *m*, so that when the bolt is thrown into the locked position the guard-plate is moved over the key-hole, and vice versa, and the guard-plate is held locked in both adjustments. This is so because the key is so formed that when inserted from the rear it will not in operation raise the pawl *j* sufficiently to disengage the slot *m* from the lever *i*. The key *o* is so formed that when inserted from the front it in operation raises pawl *j* so that slot *m* is disengaged from lever *i*, leaving the lever and guard-plate stationary while the bolt reciprocates. When the bolt is thrown into the locked position with the key inserted from the front, the top of lever *i* sinks into slot *n*, and when the operation is reversed the top of lever *i* again sinks into slot *m*.

I claim as my invention—

1. The combination of the bolt *c*, the pawl *j*, provided with the slot *m*, the lever *i*, and the guard-plate *d*, all substantially as described, and for the purpose set forth.

2. The combination of the bolt *c*, the pawl *j*, provided with the slots *m* *n*, the lever *i*, the guard-plate *d*, and the key *o*, formed to disengage the slots from the lever when inserted from one side only, substantially as described.

JOSEPH WARNER.
